UNITED STATES PATENT OFFICE.

ALMOND L. CARLOW, OF PROVIDENCE, RHODE ISLAND.

DESIGN FOR A CRIBBAGE-BOARD.

48,626.

Specification for Design.

Patented Feb. 29, 1916.

Application filed December 17, 1915. Serial No. 67,477. Term of patent 7 years.

To all whom it may concern:

Be it known that I, ALMOND L. CARLOW, a citizen of the United States, residing at Providence, in the county of Providence and State of Rhode Island, have invented a new, original, and ornamental Design for Cribbage - Boards, of which the following is a specification, reference being had to the accompanying drawings, forming part thereof.

The figure in the drawing is a perspective view of the cribbage-board, showing my design.

I claim:

The ornamental design for a cribbage-board, as shown.

ALMOND L. CARLOW.

Witnesses:

ADA E. HAGERTY,
J. A. MILLER.
